ARTHUR J. HALL, WILKINSBURG, PENNSYLVANIA, ASSIGNOR TO WESTINGHOUSE ELECTRIC & MANUFACTURING COMPANY, A CORPORATION OF PENNSYLVANIA.

ELECTRICAL SYSTEM.

Application filed October 30, 1918. Serial No. 260,307.

To all whom it may concern:

Be it known that I, ARTHUR J. HALL, a subject of the King of Great Britain, and a resident of Wilkinsburg, in the county of 5 Allegheny and State of Pennsylvania, have invented a new and useful Improvement in Electrical Systems, of which the following is a specification.

My invention relates to electrical systems 10 and particularly to the control of a circuit-breaking device under various operating conditions.

One object of my invention is to provide 15 circuit-breaking apparatus and a governing system therefor, whereby the apparatus is closed pneumatically, held closed mechanically and tripped or opened electrically.

Another object of my invention is to provide, in connection with electrical control of 20 the pneumatic closing operation of the circuit breaker, a quick-acting application and release valve, whereby the breaker is prevented from only partially closing.

A further object of my invention is to provide 25 independent electrical circuits for manually effecting the closure of the circuit breaker and for automatically effecting the opening thereof after a predetermined time interval dependent upon the overload conditions of the circuit to be protected.

Still another object of my invention is to provide 30 a simple and convenient type of remote control for a circuit breaker, whereby the most suitable locations may be selected for the circuit breaker proper and the manual-control apparatus therefor.

My invention may best be understood by 35 reference to the accompanying drawing, wherein Fig. 1 is a combined view of the electrical and pneumatic connections that are employed in my invention for operating a circuit-breaking apparatus, the electrical circuits being shown diagrammatically and the mechanical members being illustrated 40 partly in elevation and partly in section; and Fig. 2 is a view, in longitudinal section, of the quick-acting application and release valve that is employed in the system of Fig. 1.

The present apparatus is particularly applicable for use in railway locomotives or 45 the like, although it should be understood that it may also be readily applied to other types of systems wherever both a source of

electrical energy and a source of fluid pressure are available.

Referring to Fig. 1 of the drawing, the system and apparatus shown comprise a suitable main-circuit supply conductor, such as the customary trolley of a railway system, 50 which energizes a main conductor 1 on the locomotive through the agency of a suitable pantograph or trolley-wheel. The main-circuit conductor 1 of the present system is connected to the primary winding of a main 55 transformer which need not be illustrated here, since it forms no material portion of the present invention. A series transformer 2 is energized from the main-circuit conductor 1 to control a time-element relay device 60 65 70 75 80 that automatically governs the tripping coil 4 of a circuit-breaker apparatus 5, which is adapted to protect the circuit including conductor 1. A source 6 of air or other fluid pressure is employed to close the circuit-breaker apparatus 5 through the agency of an electrically-controlled valve 7 and a quick-acting application and release valve 8, auxiliary control-circuit energy being supplied by a battery B.

The time-element relay device 3 is shown 85 as comprising an actuating coil 10 that is energized from the secondary winding of the series transformer 2 to magnetize a vertically movable core member 11, the lower end 90 of which constitutes a piston 12 of metal or other electrically conducting material, floating upon a pool of mercury 13 which is contained in a receptacle 14 that is divided by a pair of suitable partitions into a central 95 compartment or chamber for housing the piston 12 and a pair of outer or side compartments that communicate with the central compartment through suitable apertures or openings near the bottoms of the partitions or inner walls.

The purpose of the piston 12 and the pool 100 of mercury 13 is to complete the control circuit of the circuit-breaker tripping coil 4, as illustrated, under normal operating conditions, as hereinafter more fully described. The operation of the time-element relay device is familiar to those skilled in the art and it is necessary to say here only that, while, under normal operating conditions, the tripping-coil circuit is closed through the pool of mercury, when a predetermined overload current obtains in the main con-

ductor 1, the actuating coil 10 is sufficiently energized to raise the piston 12 to a position that allows the mercury in the central chamber to reach the same level as that in the side 5 compartments, whereby the auxiliary circuit in question is interrupted after a predetermined time interval.

The use of a time-element relay is advantageous in that a lower current setting is 10 allowed and, therefore, a greater degree of protection is secured, without danger of opening the circuit-breaker during line-voltage surges. An opening interval of two 15 seconds for the relay will provide time for the sub-station circuit-breakers to open upon the occurrence of a heavy short-circuit.

The tripping coil 4 is located in a suitably recessed portion 20 of the circuit-breaker frame and encloses a magnetizable core 21 20 that is adapted to attract and engage a bell-crank armature or trigger member 22 that is pivoted at an intermediate point 23 upon the frame portion 20 to act as a latching member to hold the main operating arm or 25 lever 24 of the switching mechanism to its closed or circuit-completing position. A powerful spring 25 is secured to the trigger member 22 to oppose the magnetic action of the tripping coil 4, whereby, upon the de- 30 energization of the coil by the time-element relay device 3, the spring 25 rapidly actuates the armature 22 to its tripped or open position, thus releasing the arm 24 to effect the opening of the main circuit-breaker contact 35 members.

Although the illustrated circuit-breaker mechanism is particularly adapted for use in connection with an oil switch, it should be understood that my invention is not so 40 restricted in its application, but any equivalent type of circuit-breaker or switching mechanism may also be employed in connection with the present invention.

The circuit-breaker apparatus 5 is shown 45 as comprising the main operating arm or lever 24, which is pivoted at an intermediate point 26 upon a frame or supporting member 27, which may be secured to the top cover member of the oil switch, or its equivalent, in any suitable manner. The operating rod 28 for the movable member of the oil switch is connected to the end of the operating arm 24 that is remote from the latching mechanism, and a second rod or 50 piston stem 29 is pivotally mounted upon the operating lever 24 at a point intermediate the switch rod 28 and the pivotal point 26 of the arm. The lower end of the rod 29 constitutes a suitable piston 30 which 55 travels within an operating cylinder 31 and is biased to its lowermost position by a helical spring 32. Fluid pressure is admitted 60 from a pipe or passage 33 beneath the piston 30 to overcome the biasing action of the 65 spring 32 and raise the switch rod 28 to its

upper or circuit-closing position, provided a predetermined degree of air pressure is available to insure the complete closure of the switch contacts. The illustrated mechanical latching device comprising the 70 bell-crank armature 22 and the operating arm 24 thereupon engage to maintain the circuit-breaker in its closed position as long as the tripping coil 4 is energized. The complete independence of the closing and the 75 opening apparatus for the switching mechanism has the advantages of simplicity in construction and reliability of operation.

The fluid-pressure pipe 33 effects communication between the operating cylinder 80 and the quick-acting application and release valve 8, whence pneumatic connection is continued through an electrically-controlled valve member 7, a T-joint 34 and a three-way valve 35 either to a pipe 36 leading to 85 the main reservoir of fluid pressure or to an auxiliary source of fluid pressure, such as a tank 37, to which air under pressure is supplied by means of a suitable hand-pump 38 through a check valve 39 that permits the flow of air from the pump to the tank 37.

The three-way valve 35 may occupy the illustrated position *a* to permit the flow of fluid pressure from the auxiliary source or 95 tank 37 to the circuit-breaker-closing cylinder 31, or the valve may be actuated to its other operative position *m* to effect communication between the main reservoir pipe 36 and the pneumatic operating mechanism 100 for the circuit-breaker. When the locomotive has been idle and disconnected from the trolley for some time, the main reservoir pressure is either very low or entirely absent, by reason of the fact that the electric motor-driven air-compressor has not recently been employed to pump up the air pressure; and, under such circumstances, the customarily provided hand-pump 38 is operated by the handle member 45 to force air from the cylinder 46 through the check-valve 39 into the auxiliary control tank or reservoir 37 and thence, through the three-way valve 35 in its illustrated position *a*, to the T-joint 34, where the pneumatic connection divides, one 110 branch including an electrically-controlled valve member 49 comprising an actuating coil 50 and a normally closed valve 51 that is governed by the actuating coil 50, further pneumatic communication being continued 115 through pipe 52 to a trolley unlock cylinder 53, of a familiar type, for effecting the elevation of the pantograph to the supply-conductor trolley, thereby permitting the motor-driven pumps to operate and fill the main 120 reservoir.

The other pneumatic branch from the T-joint 34 comprises the electrically-controlled valve 7 which, like the valve 49, also embodies an actuating coil 54 and a normally 125 closed valve 55.

closed valve 55, the pneumatic connection further including the quick-acting application and release valve 8 and pipe 33, which leads into the circuit-breaker-closing cylinder 31.

The quick-acting application and release valve 8 is not per se of my present invention but is inserted in the illustrated pneumatic connection for the above-mentioned purpose 10 of insuring a complete closure of the circuit-breaker contact members. The valve is shown in section in Fig. 2 as comprising an outer encasing member 60 having an inlet opening 61, a supply outlet opening 62 and 15 an exhaust opening 63. An annular bearing block or cylindrical member 64, forming a part of the encasing member 60, encloses a stationary bearing sleeve 65 of brass or similar material, within which a sliding 20 valve member 66, of like material, is disposed to rest upon an annular valve seat 67, a helical spring 68 being located within the valve member 66 to bias it to the illustrated lower or closed position.

25 The operation of the valve 8 may be briefly described as follows. Air is admitted, through the inlet opening 61, to a chamber 70, as indicated by the solid arrows, to lift the sliding valve member 66 from its 30 seat 67 and permit the passage of air into an outlet chamber 71 from which the supply outlet opening 62 leads. If the air pressure is of a sufficiently high value to insure the complete closure of the circuit-breaker contact members, the sliding valve member 66 is 35 instantaneously actuated to its uppermost position to permit the passage of the full air pressure through the supply outlet opening 62 to the circuit-breaker-closing cylinder 31. However, if the air pressure is 40 relatively low and cannot effect more than a partial closure of the circuit breaker, the sliding valve member 66 is not actuated to its uppermost position, but to an intermediate 45 position that is determined by the relative forces exerted by the air pressure and the biasing spring 68, whereby the air follows the course of the dotted arrows from the outlet chamber 71 through a passage 72 located 50 just above the sliding valve member 66 and thence out, through a vertical passage 73, to the exhaust outlet opening 63. In this way, the air pressure is rapidly dissipated, and actuation of the circuit-breaker closing cylinder is precluded.

It will be understood that any other suitable device for performing the same function as that accomplished by the quick-acting application and release valve 8 may be substituted therefor.

Assuming that it is desired to actuate the circuit breaker 5 from the initially open position to the illustrated closed position, a push-button 75, conveniently located at any point remote from the circuit-breaker pro-

per, preferably in the locomotive cab near the ordinary master-controller apparatus, is pressed by the train operator to close a circuit from the positive terminal of the battery B through conductor 76, a suitable 70 train-line conductor 77, hand-switch 78, push-button 75, conductor 79, actuating coil 54 of the closing valve 7, and conductors 80 and 81, to the negative battery terminal. The valve 7 is thus opened to admit fluid 75 pressure from either the main reservoir or the auxiliary tank 37, as illustrated, through the previously traced pneumatic communicating system, to the operating cylinder 31 to effect upward movement of the piston 30 80 to the illustrated position and, therefore, the closure of the oil-switch contact members and the locking of the operating arm 24 in the previously-described manner.

Upon the release of the push-button 75, 85 the valve 7 again closes to interrupt communication with the operating cylinder 31, but the breaker is maintained in its closed position by reason of the co-operating electromagnetic action of the bell-crank armature 90 member 22 and the tripping coil 4 which, under normal operating conditions, is maintained energized through a circuit including the train-line conductor 77, conductor 82, piston 12 and mercury pool 13 of the time- 95 element relay device 3, conductor 83, tripping coil 4, conductor 84 and the negative battery conductor 81.

Upon the occurrence of a predetermined 100 overload condition in the main-circuit conductor 1, that is, in the circuit including the circuit-breaker, the time-element relay device 3 is actuated, as already described, to interrupt the connection of the mercury pool 13 with the conductor 83, thereby de- 105 energizing the tripping coil 4 and permitting the spring 25 to actuate the bell-crank armature member 22 to its open position, whereby the switch rod 28 is immediately 110 actuated to its lower or open circuit position by the spring 32 that is contained in the operating cylinder 31.

It will be seen that I have thus provided a relatively simple remote-control system 115 for operating a circuit-breaker upon a locomotive, for example, provision being made for the manually-controlled pneumatic closing, mechanical holding, and automatic electrical tripping of the circuit breaker.

I do not wish to be restricted to the specific circuit connections or arrangement and construction of parts herein set forth, as various modifications thereof may be made without departing from the spirit and scope 120 of my invention. I desire, therefore, that only such limitations shall be imposed as are indicated in the appended claims.

I claim as my invention:

1. The combination with a movable switching mechanism, of a source of fluid 130

pressure, manually-governed means for electrically opening communication between said source and said mechanism to effect the closure thereof, and means for preventing such closure unless a predetermined degree of fluid pressure obtains.

2. The combination with a movable switching mechanism, of a source of fluid pressure, a valve for normally closing communication between said source and said mechanism, manual remote-control means for electrically opening said valve to effect the closure of said switching mechanism, and a further valve interposed between the first-named valve and said mechanism for preventing said closure by dissipating the fluid pressure unless a predetermined degree of pressure obtains.

3. The combination with a movable switching mechanism, of a main source and an auxiliary source of air pressure, a hand-pump for supplying said auxiliary source, a three-way valve for establishing partial pneumatic communication between either of said sources and said mechanism, remote-control means for completing said communication to close the mechanism, and means for preventing such closure unless a predetermined degree of air pressure obtains.

4. The combination with a movable switching mechanism, of a main source of air pressure, an auxiliary source of air pressure adapted for use with both said switching mechanism and with other devices, a three-way valve for establishing partial pneumatic communication between either of said sources and said mechanism, a valve electrically actuated to complete said com-

munication to close said mechanism, and a further valve interposed between the electrically-actuated valve and said mechanism or preventing the closure of the mechanism by dissipating the air pressure unless a predetermined degree of pressure obtains.

5. The combination with a movable switching member, of a source of fluid pressure, remote-control means for governing the application of fluid pressure from said source to said member to effect a closure thereof, and means for preventing such closure by dissipating the air pressure unless a predetermined degree of fluid pressure obtains.

6. The combination with a movable switching member, of a plurality of sources of fluid pressure, means for establishing partial pneumatic communication between either of said sources and said member, remote-control means for completing said communication to close the mechanism, and means for preventing such closure unless a predetermined degree of pressure obtains.

7. The combination with a movable switching member, of a piston-and-cylinder mechanism for normally effecting the operation of said member, means for governing the application of fluid pressure to said mechanism, and means for preventing one operation of said member unless a predetermined degree of fluid pressure is available.

In testimony whereof, I have hereunto subscribed my name this 26th day of Oct. 1918.

ARTHUR J. HALL.
